[57] CLAIM

The ornamental design for an electrical connector including insulation displacing contacts, substantially as shown and described.

DESCRIPTION

FIG. 1 is a perspective view of the electrical connector including insulation displacing contacts of my new design, overlying a section of flat multiconductor electrical cable and support base, both of which are shown in phantom and form no part of the present invention; FIG. 2 is a sectional view thereof taken along line 2—2 of FIG. 1 and shown on a greatly enlarged scale; FIG. 3 is a bottom perspective view thereof, shown on a greatly enlarged scale.
